DESIGN FOR A BUCKLE OR SIMILAR ARTICLE

Harry Miller and Pierre Marcello,
New York, N. Y.

Application May 23, 1939, Serial No. 85,142

Term of patent 3½ years

To all whom it may concern:

Be it known that we, Harry Miller and Pierre Marcello, citizens of the United States of America, residing in the city of New York, county of New York, and State of New York, have invented a new, original, and ornamental Design for a Buckle or Similar Article, of which the following is a specification, reference being had to the accompanying drawing, forming part thereof.

Fig. 1 is a plan view of a buckle or similar article, showing my new design.

Fig. 2 is an edge view thereof.

Fig. 3 is a plan view slightly in perspective showing the buckle in open position.

We claim:

The ornamental design for a buckle or similar article, substantially as shown.

HARRY MILLER.
PIERRE MARCELLO.
